Attorney

UNITED STATES PATENT OFFICE.

HARRY BLUM, OF JOHNSTOWN, PENNSYLVANIA.

SAFETY-RAZOR.

1,313,980.

Specification of Letters Patent. Patented Aug. 26, 1919.

Application filed January 22, 1918. Serial No. 213,148.

To all whom it may concern:

Be it known that I, HARRY BLUM, a citizen of Russia, residing at Johnstown, in the county of Cambria and State of Pennsylvania, have invented certain new and useful improvements in Safety-Razors, of which the following is a specification.

This invention relates to new and useful improvements in safety razors, and the primary object of this invention is to provide a simple and efficient device of this character which is so constructed, that the ordinarily inaccessible places on the user's face may be easily reached, and said razor is easily detached, so that same may be kept clean and sanitary.

A further object of the invention is to provide a device of this character, which is easily and simply constructed, inexpensive to manufacture, and one which will be very efficient in operation.

With these and numerous other objects in view, my invention consists of the novel features of construction, combination, and arrangement of parts which will be herein referred to and more particularly pointed out in the specification and claim.

In the accompanying drawings:

Figure 1 is a plan view of the razor, the parts in connected position, showing the portion of the handle connection in section,

Fig. 2 is a transverse section through the guard and blades,

Fig. 3 is a longitudinal section, and

Fig. 4 is a transverse section through the connection between the guard and handle.

In describing my invention, I shall refer to the drawings, in which similar reference characters designate corresponding parts throughout the several views.

The numeral 1 designates a guard plate for this type of safety razor, said guard plate being provided with a longitudinally extending slot 2 therein, said slot having shoulder portions 3 that form guide means, as will be hereinafter more fully described. The opposite sides of the guard plate 1, are inclined as clearly shown at 4, so that a blade 5 correspondingly shaped to said plate may be positioned thereon. This blade owing to the peculiar shape of the same and plate greatly increases the efficiency of a razor so constructed, as it is to permit places otherwise inaccessible on the user's face to be easily reached.

The blade 5 is provided with a longitudinally extending slot 6 therein corresponding to the slot 2 in the guard plate, and when the blade is positioned on the plate, the two slots 60 aline.

The inner end of the plate 1 is provided with an enlarged portion 7, which extends rearwardly and has the extremity thereof externally threaded as shown at 8, said enlarged portion and projection 8 being 65 grooved as at 9 to receive one end of a holder 10 employed in this device. The holder 10 comprises a flat bar having on one end an enlarged portion 11, with an inclined outer face 12 which is adapted to be positioned 70 within the groove 9, and when so arranged to be securely held in said position by operatively connecting therewith an internally threaded end portion 13 of a handle 14 for the razor. The handle 14 is preferably constructed of metal, and is secured on the part 13, which is also formed of metal. When the various parts of the connection are assembled as clearly shown in Figs. 1 and 3 of the drawings, the holder will be securely 75 locked in position.

The free end of the holder 10 extends along the blade 1 over the inner end of the alining slot in said plate and blade. The end portion of the holder which is designated by the numeral 15 is formed with projecting flanges 16 and 17 on its opposite sides at the upper and lower edges thereof, the flanges 16 being adapted to be positioned upon the shoulder portions 3 of the slot 2 within 80 the guard plate, while the flanges 17 engage the opposite edges of the slot 2 of the blade 5. This connection is clearly shown in Fig. 2 of the drawings.

In operation, when the various parts of 95 the razor are assembled as clearly shown in Figs. 1 and 2 of the drawings, the device is in operative position. After use, when it is desired to remove the blade to clean the device, the portion 13 is unscrewed from the 100 connection with the blade 1, and this permits the holder 10 to be moved longitudinally. Its inner end that is positioned in the alining slots, will move along the same to the outer end, whereupon the blade 5 may be 105 easily removed from the plate 1. This disassembling operation is very simple, and the opposite assembling of the parts of the device will be likewise.

Owing to the peculiar construction of the 110

blade and guard, this type of razor will be most advantageous, and owing to the extreme simplicity of assembling and disassembling of the parts, and their flat construction, the device may be kept absolutely sanitary with very little trouble.

From the above description taken in connection with the accompanying drawings, it is thought that a clear and comprehensive understanding of the construction, operation, and advantages of my invention may be had, and while I have shown and described the device as embodying a specific structure, I desire that it be understood that such changes may be made in said structure as do not depart from the spirit and scope of the invention as claimed.

Having fully described my invention,

what I claim as new, and desire to secure by Letters Patent, is:

In a safety razor the combination with a blade formed with a longitudinally extending slot, a guard plate having a corresponding slot, one end of said plate being externally threaded and longitudinally grooved, a holder having a projecting portion on one end thereof slidably mounted in the alining slots, said end of the holder being adapted to clamp the blade to the plate, and a handle engageable with the externally threaded end of the holder plate and adapted to clamp the holder in locked position to securely hold the blade to the plate.

In testimony whereof, I affix my signature hereto.

HARRY BLUM.
